(57) CLAIM

The ornamental design for a travel tray for children, as shown and described.

DESCRIPTION

FIG. 1 is a perspective view of the travel tray for children; FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a perspective view of a tray base of the travel tray for children;

FIG. 9 is a front view thereof;

FIG. 10 is a back view thereof;

FIG. 11 is a right side view thereof;

FIG. 12 is a left side view thereof;

FIG. 13 is a top view thereof;

FIG. 14 is a bottom view thereof;

FIG. 15 is a perspective view of a tray insert of the travel tray for children;

FIG. 16 is a front view thereof;

FIG. 17 is a back view thereof;

FIG. 18 is a right side view thereof;

FIG. 19 is a left side view thereof;

FIG. 20 is a top view thereof; and,

FIG. 21 is a bottom view thereof.

The broken lines in the drawings depict portions of the Travel Tray for Children that form no part of the claimed design. The dash-dot-dash broken lines shown in FIGS. 1, 6, 7, 14, 15, 20, and 21 are for the purpose of disclosing the boundaries of the claimed design and form no part of the claimed design.

1 Claim, 21 Drawing Sheets
